UNITED STATES PATENT OFFICE.

BRUCE D. WOOLLEY, OF JOHNSTOWN, OHIO.

VENDING MACHINE.

Application filed January 13, 1926. Serial No. 81,109.

My invention relates broadly to a vending machine and, more particularly, to a coin controlled apparatus for delivering sanitary toilet seat covers from a container 5 which may be conveniently located in public toilets.

The primary object of my invention is to provide a simple, compact, positive and reliable machine for vending sanitary toilet seat covers from a connected series of such covers positioned within a container.

A further object of my invention is to provide means operating responsively to movement of the covers for securing the vending mechanism against further operation when a cover has been delivered.

Other objects of my invention will appear from the following description and all features are illustrated in the accompanying drawings wherein similar reference numerals designate similar parts in the several figures, and wherein—

Figure 1 is a perspective view having parts broken away to show the vending mechanism and interior arrangement of my novel machine;

Figure 2 is a transverse vertical sectional view showing the pawl disengaged from the ratchet and the parts in position for delivering a cover;

Figure 3 is a transverse vertical sectional view similar to Figure 2 but showing the coin released and the pawl ready to reengage the ratchet; and

Figure 4 is a plan view showing one complete commode seat cover and its relation to adjacent covers.

With reference to the drawings and particularly to Figure 1, it will be seen that my invention comprises a case or container 1 which may be equipped with a lid 2 mounted for movement about pivot rod 3, which may be enclosed by a reinforcing roll 4. The lid 2 may be provided with a lock 5 which is adapted to engage with the container 1 as at 6 to secure the cover in closed position and so prevent tampering with the vending mechanism. It will be noted that the cover 2 overlaps the container 1 and is effective to prevent removal of coins from the machine.

Within the container 1 are provided bearings 7, which are designed to support a shaft 8 for carrying a tube 9, upon which a series of sanitary toilet seat covers of the type shown in Figure 4 may be wound. The shaft 8 is preferably removable from the bearings 7 and container 1 to make possible mounting of a new roll of covers. The connected covers 10, which are unwound from the roll as the machine is operated, are carried downwardly under an idler 11 and then between the spring plate 12 and friction effective delivering rollers 13 on the shaft 14, which may also be provided with a crank or similar actuating means 15 for delivering covers from the apparatus after the vending mechanism has been released as hereafter described.

The lid 2 may be formed with a slot 16 of a size to admit coins of the required denomination, and this slot registers with the upper end of an inclined slide 17, which may be attached to container 1 as best shown in Figure 1. A coin receiving receptacle 18 may be positioned within the container in alignment with the slide 17 and is preferably formed in the shape of a cup to prevent coins from being extracted therefrom.

The brackets 19 which are secured to the container 1, in addition to the idler 11, also carry a rod 20 which may have a tongue or pawl 21 and levers 22 and 23 secured thereto. The lever 22 normally extends into slide 17 far enough to stop coins of the correct denomination but not far enough to stop spurious small sized articles which might be deposited in slot 16. The lever 23, at its outer end, may be formed with a pawl portion 24 which normally engages with the teeth on the ratchet wheel 25, which is securely mounted on shaft 14. The tongue 21 and levers 22 and 23 are all secured to shaft 20 so that movement of any one effects a corresponding movement of the others, as will be more fully described hereafter.

The operation of my novel vending machine is as follows: All parts are normally in the positions shown in Figure 1 and when a suitable coin or check 26 is deposited in slot 16 it will first traverse the inclined

slide 17 and lodge under lever 22, which at the same time will be slightly elevated, and this elevation of lever 22 will be effective to disengage the pawl portion 24 of lever 23 from the teeth of ratchet wheel 25, as clearly shown in Figure 2. When the pawl portion 24 of lever 23 has been disengaged from the teeth of ratchet wheel 25 as just described, the crank 15 may be revolved and the friction wheels 13, which may be formed of rubber or some other suitable material, will frictionally engage and deliver a cover from the container through opening 29. As the cover is advanced through opening 29, the tongue 21 will extend through the central opening 27 of the cover and function as a counterweight to retain coin 26 under lever 22 but as the cover continues to advance, the tongue 21 will be engaged by portion 28 of the cover and elevated, and this movement of tongue 21 will elevate lever 22 and so permit the coin 26 to roll into the receiving receptacle 18, as shown in Figure 3. The cover continues to advance, and tongue 21 presently drops into opening 27 of the next succeeding cover and allows the lever 22 to assume its normal position and the pawl portion 24 of lever 23 to again engage with the teeth of ratchet wheel 25 and prevent further operation until another coin is deposited in slot 16.

When a complete cover has been delivered through opening 29, it may be separated from the other covers within the container by tearing along the perforated portion 30, which at this time will be substantially coincident to opening 29. Each succeeding cover is obtained in the same manner, that is, by depositing a coin in the slot 16 and turning the crank 15 as previously described. A pawl 31 and ratchet wheel 32 secured to shaft 14 may be employed for preventing reverse movement of crank 15.

From the foregoing description, it will be apparent that I have invented a machine for vending sanitary toilet seat covers which is simple in design and construction, positive in operation, substantially built and cheap to manufacture.

50 Claims:

1. A device of the class described comprising a casing, means for supporting a roll of covers in said casing, said covers having cut out portions, means for feeding said covers from said casing, and coin controlled mechanism for permitting the operation of said feeding means comprising a rod, an elbow shaped member having projections extending from each end of said member fixedly mounted upon said rod, one of said projections being adapted to lock said feeding means, and the other of said projections being adapted to engage a coin, and means fixedly mounted upon said rod extending within an opening defined by a cut out por-

tion of said covers adapted to engage an edge of said cut out portion as the covers are moved to permit the coin to be released from said coin engaging projection and to cause said locking projection to engage said feeding means after the coin is released.

2. A device of the class described comprising a casing, means for supporting a roll of covers in said casing, said covers having cut out portions, means for feeding said covers from said casing, locking means carried by said feeding means, and coin controlled mechanism for permitting the operation of said feeding means comprising a rod, an elbow shaped member having projections extending from each end of said member fixedly mounted upon said rod, one of said projections being adapted to engage said locking means, and the other of said projections being adapted to engage a coin, and means fixedly mounted upon said rod extending within an opening defined by a cut out portion of said covers adapted to engage an edge of said cut out portion as the covers are moved to permit the coin to be released from said coin engaging projection and to cause said lock engaging projection to engage said locking means after the coin is released.

3. A device of the class described comprising a casing, means for supporting a roll of covers in said casing, said covers having cut out portions, means for feeding said covers from said casing, locking means carried by said feeding means, and coin controlled mechanism for permitting the operation of said feeding means comprising a coin chute, a rod, an elbow shaped member having projections extending from each end of said member fixedly mounted upon said rod, one of said projections being adapted to engage said locking means, and the other of said projections being adjacent said coin chute and adapted to engage a coin, and a tongue shaped member fixedly mounted upon said rod extending within an opening defined by a cut out portion of said covers adapted to engage an edge of said cut out portion as the covers are moved to permit the coin to be released from said coin engaging projection and to cause said lock engaging projection to engage said locking means after the coin is released.

4. A device of the class described comprising a casing, means for supporting a roll of covers in said casing, said covers having cut out portions, an operating shaft for feeding covers from said casing, locking means mounted upon said shaft, and coin controlled mechanism for permitting the actuation of said operating shaft comprising a rod, an elbow shaped member having projections extending from each end of said member fixedly mounted upon said rod, one of said projections being adapted to engage said lock-

ing means and the other of said projections being adapted to engage a coin, and a tongue shaped member fixedly mounted upon said rod extending within an opening defined by a cut out portion of said covers adapted to engage an edge of said cut out portion as the covers are moved to permit the coin to be

released from said coin engaging projection and to cause said lock engaging projection to engage said locking means after the coin is ¹⁰ released.

In testimony whereof I hereby affix my signature.

BRUCE D. WOOLLEY.
